UNITED STATES PATENT OFFICE.

HARRY B. BASS, OF YUKON, OKLAHOMA.

DOOR ATTACHMENT.

1,290,488.

Specification of Letters Patent.

Patented Jan. 7, 1919.

Application filed April 18, 1917. Serial No. 162,962.

To all whom it may concern:

Be it known that I, HARRY B. BASS, a citizen of the United States, residing at Yukon, in the county of Canadian and State of Oklahoma, have invented a new and useful Door Attachment, of which the following is a specification.

The present invention relates to a device for attachment to outside doors, screen doors, automobile doors and the like, whereby to snugly hold the door in place when closed, to prevent rattling thereof, and to enable the door to be readily opened and closed without binding or sticking, due to the warping or distortion thereof.

It is the object of the invention to provide an attachment of the nature indicated which is extremely simple and inexpensive in construction, yet thoroughly practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawings, wherein:—

Figure 1 is a longitudinal section of the attachment, portions being shown in elevation.

Fig. 2 is an enlarged longitudinal sectional detail of the device.

Generally considered, the device embodies a pair of elongated members telescoped 40 transversely with spring means therebetween, one of the members being attached to the edge of a door and the other being yieldably projected to engage with the door frame. One of said members embodies an elongated strip or base 1 having attaching 45 holes 2, and provided with a continuous apron 3 providing an elongated pocket, the terminals of the strip 1 projecting beyond the ends of the apron 3 to form tongues 4 which can be secured by screws (not shown) 50 inserted through holes 5 to the door. These tongues 4 may be left in the plane of the strip 1 or can be bent at an angle flush with the ends of the apron 3, for attachment to 55 the adjacent edges of the door.

The other member 6 is in the form of an elongated trough or receptacle having its rim fitted snugly and slidably within the apron 3, whereby the two members are telescoped for parallel motion. The bottom 60 portion of the member 6 is rounded, as at 7, to move readily into engagement with the threshold or jamb of the door frame or casing, the floor, and over or past other parts without catching. The two members 65 in fitting snugly together in telescopic arrangement, provide a transversely extensible elongated device having an inclosed chamber in which the spring means is housed for yieldably projecting the member 6.

In the modified form shown coiled retractile springs 8' are used adjacent to the ends of the member 6 within the same, one end of each of said springs being engaged 75 with a hook 10' with which the end of the member 6 is provided, the other ends of the spring being engaged with hooks 11' with which rigid hangers or depending rods 9' are provided, said hangers or rods being 80 rigidly secured at their upper ends to the strip 1 near the ends of the apron 3 so as to hang within the member 6, the hooks 11' co-acting with the ends of the member 6 to aid in guiding the latter.

Having thus described the invention, what is claimed as new is:—

A door attachment comprising a first member including a base, and a second member 90 slidable transversely in the first member and having ends; rods secured to the base of the first member and projecting within the second member, the rods having outwardly extended first hooks co-operating with the ends of the second member to aid 95 in guiding the latter; inwardly projecting second hooks secured to the ends of the second member between the first hooks and the base; and retractile springs having their ends mounted on the first and second hooks. 100

In testimony that I claim the foregoing as my own, I have hereto affixed my signature in the presence of two witnesses.

HARRY B. BASS.
